UNITED STATES PATENT OFFICE.

SAMUEL H. JONES, OF SCRANTON, PENNSYLVANIA, ASSIGNOR OF TWO-THIRDS TO WADE M. FINN, OF SAME PLACE, AND JOHN B. SHANNON, OF CARBONDALE, PENNSYLVANIA.

DESIGN FOR A FILTERING-FAUCET BODY.

SPECIFICATION forming part of Design No. 31,824, dated November 14, 1899.

Application filed August 29, 1899. Serial No. 728,916. Term of patent 7 years.

To all whom it may concern:

Be it known that I, SAMUEL H. JONES, a citizen of the United States, residing at Scranton, in the county of Lackawanna and State of Pennsylvania, have invented and produced a new and original Design for a Filtering-Faucet Body, of which the following is a specification.

As shown in the accompanying drawing, my design consists of a rounded portion 1, having its largest diameter at the center and narrowing toward the ends, the central portion being surmounted by a conical part 2, above which is an overhanging cap 3, having angular faces 4 and the curved upper surface 5. The portion 1 enlarges at the rear end 6 and is formed with angular faces 7. The opposite end of the part 1 merges into a conical part 8, arranged at right angles thereto, said part 8 having at its lower and smaller end a

cap 9, rounded on the bottom, as shown, and having angular faces 10. Above the conical portion 8 is a tubular part 11, enlarging at the bottom, as shown at 12, and having angular faces 13 overhanging the conical portion 8. Said part 11 curves outwardly and downwardly, as shown at 14, its end being exteriorly screw-threaded, as shown at 15. Above the threaded end is an annular bead 16.

Having described my invention, what I claim is—

The design for a filtering-faucet body, substantially as shown and described.

In testimony whereof I affix my signature in presence of two witnesses.

SAMUEL H. JONES.
